DESIGN FOR A BOOK COVER OR SIMILAR ARTICLE

Frances Stephens, New York, N. Y.

Application November 18, 1941, Serial No. 104,186

Term of patent 14 years

To all whom it may concern:

Be it known that I, Frances Stephens, a citizen of the United States of America, residing in New York city, county of New York, and State of New York, have invented a new, original, and ornamental Design for a Book Cover or Similar Article, of which the following is a specification, reference being had to the accompanying drawing, forming part thereof, wherein the figure of the drawing is a plan view of a book cover or similar article showing my new design.

It is to be understood that the cross hatching shown only in parts of the book cover, representing buckram, is continued throughout the face of the book cover.

The dominant features of the design reside in the portions shown in solid lines.

I claim:

The ornamental design for a book cover or similar article, substantially as shown, and described.

FRANCES STEPHENS.
